Primary Examiner — Omeed Agilee(74) *Attorney, Agent, or Firm* — Ballard Spahr LLP(57) **CLAIM**

The ornamental design for a medical treatment device, as shown and described.

DESCRIPTION

FIG. 1 is a perspective view of a medical treatment device showing our new design;

FIG. 2 is a bottom plan view of the medical treatment device of FIG. 1;

FIG. 3 is a top plan view of the medical treatment device of FIG. 1;

FIG. 4 is a right side elevational view of the medical treatment device of FIG. 1;

FIG. 5 is a left side elevational view of the medical treatment device of FIG. 1;

FIG. 6 is a rear elevational view of the medical treatment device of FIG. 1; and,

FIG. 7 is a front elevational view of the medical treatment device of FIG. 1.

The dashed lines in the drawings depict portions of the medical treatment device that form no part of the claimed design.

(Continued)

The dot-dash lines in the drawings depict symbolic break lines. The symbolic break lines and any portion between those lines form no part of the claimed design.

1 Claim, 5 Drawing Sheets
